SLAGGING FURNACE INSTALLATION

William J. Vogel, Montclair, N. J., assignor to International Combustion Engineering Corporation, New York, N. Y., a corporation of Delaware

Application May 22, 1931. Serial No. 539,263

3 Claims. (Cl. 110—1)

This invention relates to improvements in furnace installations and has particular reference to furnaces adapted to be operated with a bed of slag maintained in the bottom thereof.

5 One of the primary objects of my invention is the provision of an improved slag retaining floor or bottom for such furnaces.

Another object is the provision of a bottom for slagging furnaces having means for effectively protecting certain parts against damage by high temperatures.

More specifically it is an object of my invention to effectively cool the lower portion of the floor by absorbing the heat which is conducted through the floor.

I also contemplate returning the heat thus obtained through the floor.

absorbed into the combustion chamber of the furnace, either directly or through a milling or pulverizing system associated with the furnace.

20 A further object resides in providing a metallic backed floor for slagging furnaces having protective means associated therewith.

25 How the foregoing, together with such other objects and advantages as may hereinafter appear, or are incident to my invention, are realized is illustrated in the preferred form in the accompanying drawings, wherein—

Fig. 1 is a sectional elevation of a furnace installation embodying my invention.

30 Fig. 2 is a fragmentary view of the lower portion of the furnace, the right hand half of which is in section as taken on the line 2-2 in Fig. 1, and the left hand half of which is in elevation.

5 Figs. 3, 4 and 5 are enlarged fragmentary cross sections through the floor showing modifications in the floor construction.

Fig. 6 illustrates a milling or pulverizing and burner arrangement of the direct firing type in association with the furnace, the milling system being shown in elevation and a portion of the furnace being shown in section.

Fig. 7 illustrates a milling system associated with the furnace in a modified arrangement.

Fig. 8 illustrates an arrangement adapted to withdraw heated air from the bottom of the furnace and to return the heated air directly into the combustion chamber of the furnace.

Referring now more particularly to Figs. 1 and 2, the installation comprises, in general, a furnace A having a slag retaining bottom B, i. e., a bottom adapted to maintain a bed of molten slag, burner means C for introducing finely divided fuel, such as pulverized coal, and air into the combustion chamber at points adjacent the slag

bed, and a boiler D located above the combustion chamber of the furnace.

The combustion chamber E of the furnace A has its upright walls lined with steam evaporating tubes 9 which receive water by means of suitable downcomers 10, 10a and 10b and lower headers 11, 11a and 11b communicably connecting a water space or spaces of the boiler with the lower ends of the tubes. The upper ends of the tubes 9 are connected to a steam space of the boiler by means of suitable upcomers 12, 12a, 12b and 12c and upper headers 13, 13a, 13b and 13c. The rows of wall tubes are backed by suitable sheathing 14.

The bottom B of the furnace preferably comprises a layer of refractory material 15 having an upper lining 16 of "dolomite" or similar material, which lining is cupped to maintain a substantial bed of molten slag as indicated at 17. The bottom surface of the refractory layer 15 is backed by a metallic plate or plates 18 and the floor as a whole is supported by means of structural beams such as the I-beams 19 and 20. The molten slag may be tapped from the slag retaining bottom by means of a suitable tap opening 25 or spout 21.

A recess 22 is provided in the lower face of the refractory bottom 15 for the accommodation of a multiplicity of metallic cooling tubes 23, which tubes in this instance rest on the metallic backing 18. The recess 22 is of greater length than the length of the tubes 23 so that chambers 24 and 25 are provided adjacent the ends of the tubes. The chamber 24 is provided with an inlet opening 26 for the admission of atmospheric air and the chamber 25 is provided with an air outlet opening 27. It will thus be seen that air enters the tubes at their ends which are open to the chamber 24 and leaves the tubes at their ends which are open to the chamber 25, suitable means being provided to cause circulation of the air as will now appear.

Referring now more particularly to Fig. 6, it will be seen that the chamber 25 communicates with a duct 28 leading from the outlet opening 27 to the inlet portion 29 of a pulverizing mill 30 which is incorporated in a milling system 31 associated with the furnace. Thus air is drawn through the tubes 23 by means of the suction at the inlet side of the milling system. The suction is produced by a fan integral with the mill, as is usual with the unit type of mill disclosed. The air thus drawn through the tubes 23 absorbs the heat conducted through the slagging floor of the furnace and through the walls of the tubes 55

thereby cooling the lower portion of the floor and maintaining the metallic backing of the floor at a temperature much below that which might cause damage. The heated air passes through the milling system 31 and ultimately is introduced back into the furnace A with pulverized fuel by means of the conduit 32 and burner means C and thus effects a saving in heat.

In Fig. 7 heated air is withdrawn from the furnace bottom by means of a conduit 33 leading to a low pressure point 34 in the pulverizing system 35, which system delivers coal to a storage bin 36 in a well known manner, i.e., by delivering the coal and air mixture from the mill by means of the fan 35a to a cyclone separator (not shown) from which the separated coal passes to the storage bin 36, the coal free air from the cyclone separator being returned to the mill through the return line 39. An amount of air is withdrawn from the system corresponding to the amount of heated air introduced at 34. The withdrawn air may be delivered back to the furnace A. In the system shown a conduit 37 having a blower 38 therein delivers air from the return line 39 of the system to the burner line 40. Pulverized coal from the bin 36 is fed into the line 40 for delivery to the burner. It will thus be seen that in the arrangement shown in Figs. 6 and 7 the heated air which is withdrawn from the slagging bottom of the furnace is utilized for drying purposes in the milling system.

In Fig. 8 I have illustrated a modified arrangement in which the heated air is withdrawn from the slagging bottom of the furnace by means of a conduit 41 connected to the inlet side of a blower 42. The blower 42 has its discharge end connected to a conduit 43 which, in turn, is connected to a pipe 44 discharging into the combustion chamber of the furnace A at 45. Through this arrangement the air which is heated in passing through the tubes 23 of the furnace floor is delivered directly into the combustion chamber of the furnace. A damper 46 may be provided in the pipe line 44 to control the admission of heated air. It is to be understood that a plurality of pipes 44 may be provided.

In the modification illustrated in Fig. 3 I have shown the metallic tubes 23 embedded in plastic refractory or other insulating material 23a. As a further modification I have illustrated an arrangement in Fig. 4 in which a layer of insulating material 23b is provided between the metallic backing 18 and the tubes 23.

trated in which air passages 23c for the cooling air are formed directly in the lower face of the refractory layer 15 of the floor B. These passages may be formed of hollow refractory tiles or by laying refractory brick in a manner to form ducts for the passage of air. The metal construction, i. e., the form in which I employ metallic tubes, is preferable, however, for the reason that the air passages are maintained free of obstruction. This metal construction also obviates the possibility of drawing furnace gases or slag through any crevices or openings which may form in the furnace floor into the air passages. The number and size of the cooling tubes or passages is such that air in sufficient quantity for absorbing the heat conducted through the floor is circulated through the tubes or passages.

I claim:

1 claim.—
1. In a furnace adapted to be operated with
a bed of slag maintained in its lower portion in 20
a stagnant condition, the combination of a slag
retaining bottom for the furnace, a plurality of
cooling ducts in said bottom at its lower face,
chambers in said bottom located at the ends of
said ducts and communicating therewith, an air
inlet to the chamber at one end of the ducts, an
air outlet from the chamber at the other end of
the ducts, said inlet and outlet being in the lower
face of said bottom, and open work supporting
structure for said bottom. 30

2. In a furnace adapted to be operated with a bed of slag maintained in its lower portion in stagnant condition, the combination of a slag retaining bottom for the furnace having a multiplicity of closely spaced metallic tubes extending thereacross, means for passing a cooling medium through said tubes, and open work supporting structure for said bottom including a plurality of spaced beams arranged so that said metallic tubes span them.

3. In a furnace adapted to be operated with a bed of slag maintained in its lower portion in stagnant condition, the combination of a slag retaining bottom for the furnace having its lower portion constructed of refractory, metallic tubes extending across the major portion of the lower face of said refractory, spaced supporting beams for said bottom, said metallic tubes and beams being arranged so that the tubes span said beams and provide with the beams supporting means for the bottom, and means for passing a cooling medium through said tubes.

WILLIAM J. VOGEL.
